UNITED STATES PATENT OFFICE.

ARCHIBALD McLAREN, OF CLEVELAND HEIGHTS, OHIO.

SCAFFOLD BRACKET.

Application filed July 12, 1924. Serial No. 725,717.

To all whom it may concern:

Be it known that I, ARCHIBALD McLAREN, a citizen of the United States, and a resident of Cleveland Heights, county of Cuyahoga, and State of Ohio, have invented a new and useful Improvement in Scaffold Brackets, of which the following is a specification, the principle of the invention being herein explained and the best mode in which I have 10 contemplated applying that principle, so as to distinguish it from other inventions.

The present invention relates to a folding scaffold bracket which may be applied to the side wall of a frame structure by merely 15 hooking one end of the bracket around one of the uprights, the entire bracket being so arranged as to maintain itself securely in position without danger of slipping and without being secured to the building by means 20 of nails or spikes. The bracket consists essentially of a main bar with the hook on one end adapted to engage around one of the uprights, and to this bar is pivoted a supporting member adapted to have its free 25 end rest against the wall of a structure so as to support the bracket. In addition to this there is a triangular bracing member adapted to engage with the main bar so as to hold the hook in place around the studding, and this member also is adapted to 30 prevent the bracket from pivoting around the hook. To the accomplishment of the foregoing and related ends, said invention, then, consists of the means hereinafter fully 35 described and particularly pointed out in the claims.

The annexed drawing and the following description set forth in detail certain mechanism embodying the invention, such 40 disclosed means constituting, however, but one of various mechanical forms in which the principle of the invention may be used.

In said annexed drawing:

Fig. 1 is a perspective view of my improved scaffold bracket as applied to a portion of a building wall; Fig. 2 is a side elevational view of the bracket when folded; Fig. 3 is a sectional view on the line 3—3 in Fig. 1; Fig. 4 is a sectional view on the 50 line 4—4 in Fig. 1; and Fig. 5 is a sectional view on the line 5—5 in Fig. 1.

The present scaffold bracket consists essentially of a main bar 1 having a hook 2 formed at the rear end of a size to engage 55 around the usual two inch upright or studding 3 of the wall 4 of a house or other

building, and this bar has at its other end a slight upward projection 5 so as to prevent the scaffold board 30 (shown in dotted lines) from slipping off the front of the bracket. 60 Secured near the forward end of the bar is a supporting member 6 formed of inverted T-shape in cross section, and this member is pivotally attached by means of a suitable bolt or rivet 7 to the main supporting bar 65 and has its attaching end curved so as to engage with the supporting bar at substantially right angles thereto. This attached end of the supporting member has the horizontal flange 8 cut away so as to 70 limit the downward pivotal movement of the member and thus act as a stop and a support in addition to the bolt which holds it in place. At the other end the vertical flange 9 of the T-shaped member is cut away 75 and the horizontal flange is bent downwardly so as to engage with its flat surface 10 the boards 17 of the wall from which the bracket is supported.

In addition to the stop at the front end, 80 the rear end of the member is supported from the main bar by means of a pivotal link 11 having a hook 12 at its upper end which engages over the main bar and spaces the rear of the supporting member at the 85 correct distance below the bar.

To correctly position the bracket in place and to prevent sidewise or pivotal movement around the hook, the bracket is provided with a locking triangular brace member 13 formed of strap metal, the two ends 14 forming the apex of the triangle and being pivotally secured to the main bar by means of a bolt or rivet 15, and this member has the base 16 of the triangle parallel to 95 the boards 17 of the wall on which the bracket is to be supported and closely adjacent to such boards, the member being spaced with its base at such a distance from the hooked end as to allow the base to clear 100 the usual siding boards which are applied over the studding. In order to hold this triangular brace in position, the base member is bent at its central point to provide a locking recess 20 which fits over the main 105 bar, as best shown in Fig. 5, and thus prevents sidewise twisting of the triangular member so as to hold it always in place with the base parallel to the wall boards.

When not in use, the bracket may be folded up into the position best shown in Fig. 2, in which position it will be seen that the

triangular brace retains the same position as shown in Fig. 1, but the supporting member is folded up parallel to the main bar and the holding link for the supporting member 5 is folded down parallel with and adjacent to the vertical flange of the supporting member.

In using the present bracket, the triangular brace member is moved upwardly so as 10 to allow the main bar to be hooked over one of the uprights, and the brace is then moved into its locking position and the supporting member is dropped until it is stopped by the hooked link so that the lower end 15 rests flat against the boards of the wall. The bracket is then held securely in place and does not need to be nailed or in any other way secured, and it may be easily removed when desired.

20 By use of the triangular inverted T-shaped supporting member, the point of attachment between the supporting member and the main bar is made safe by the cutting away of the horizontal flange so as to provide a stop at this point to limit the pivotal movement of the supporting member away 25 from the main bar. All of the parts of the present bracket are simple to manufacture and easy to assemble, and the entire bracket 30 is easily mounted in place and taken down or moved when desired.

Other modes of applying the principle 35 of my invention may be employed instead of the one explained, change being made as regards the mechanism herein disclosed, provided the means stated by any of the following claims or the equivalent of such stated means be employed.

I therefore particularly point out and 40 distinctly claim as my invention:—

1. In a scaffold bracket, the combination of a main supporting bar provided with a hook at the inner end adapted to engage an upright, a supporting member pivotally 45 connected to said main bar near the end opposite to said hook and having limited angular movement away from said bar, and a triangular brace member pivoted to said bar and with its base parallel to the wall 50 boards and provided with means for engaging said bar to prevent relative sidewise movement between said bar and said brace.

2. In a scaffold bracket, the combination of a main supporting bar provided with a hook at the inner end adapted to engage an 55 upright, a supporting member of inverted T-shape in cross section, having its outer end curved and with the horizontal flange cut away, said end being pivotally attached to said main bar near its outer end, the pivotal angular movement away from said bar being limited by the end of the horizontal flange, and a triangular brace member pivoted to said bar and with its base parallel 60 to the wall boards and provided with means 65

for engaging said bar to prevent relative sidewise movement between said bar and said brace.

3. In a scaffold bracket, the combination of a main supporting bar provided with a hook at the inner end adapted to engage an upright, a supporting member pivotally connected to said main bar near the end opposite to said hook and having limited angular movement away from said bar, and a triangular brace member pivoted to said bar and with its base parallel to the wall boards and provided with a recess at the central point of its base member adapted to engage over said main bar to prevent relative sidewise movement therebetween. 70

4. In a scaffold bracket, the combination of a main supporting bar provided with a hook at the inner end adapted to engage an upright, a supporting member of inverted T-shape in cross section having its outer end curved and with the horizontal flange cut away, said end being pivotally attached to said main bar near its outer end, the pivotal angular movement away from said bar being limited by the end of the horizontal flange, and a triangular brace member pivoted to said bar and with its base parallel to the wall boards and provided with a recess at the central point of its base member adapted to engage over said main bar to prevent relative sidewise movement therebetween. 75

5. In a scaffold bracket, the combination of a main supporting bar provided with a hook at the inner end adapted to engage an upright, a supporting member of inverted T-shape in cross section having its outer end curved and with the horizontal flange cut away, said end being pivotally attached to said main bar near its outer end, the pivotal angular movement away from said bar being limited by the end of the horizontal flange, a triangular brace member pivoted to said bar and with its base parallel to the wall boards and provided with a recess at the central point of its base member adapted to engage over said main bar to prevent relative sidewise movement therebetween, and a supporting link pivotally connected to the free end of said supporting member and provided with a hook at its upper end adapted to engage over the main bar to limit downward movement of said supporting member. 90

6. In a scaffold bracket, the combination of a main supporting bar provided with a hook at the inner end adapted to engage an upright, a supporting member of inverted T-shape in cross section, having its outer end curved and with the horizontal flange cut away, said end being pivotally attached to said main bar near its outer end, the pivotal angular movement away from said bar being limited by the end of the horizontal flange, and a triangular brace member pivoted to said bar and with its base parallel to the wall boards and provided with means 95

- zontal flange, the free end of said supporting member having the vertical flange cut away and the horizontal flange bent to form a wall contacting flat end, a triangular brace member pivoted to said bar and with its base parallel to the wall boards and provided with a recess at the central point of its base member adapted to engage over said main bar to prevent relative sidewise movement therebetween, and a supporting link pivotally connected to the free end of said supporting member and provided with a hook at its upper end adapted to engage over the main bar to limit downward movement of said supporting member. 25
- 5 7. In a scaffold bracket, the combination of a main supporting bar provided with a hook at the inner end adapted to engage an upright, a supporting member of inverted T-shape in cross section, having its outer end curved and with the horizontal flange cut away, said end being pivotally attached to said main bar near its outer end, the pivotal angular movement away from said 30
- 10 main bar being limited by the end of the horizontal flange, the free end of said supporting member having the vertical flange cut away and the horizontal flange bent to form a wall contacting flat end, a triangular brace member pivoted to said bar and with its base parallel to the wall boards and provided with a recess at the central point of its base member adapted to engage over said main bar to prevent relative sidewise movement therebetween, and a supporting link pivotally connected to the free end of said supporting member and provided with a hook at its upper end adapted to engage over the main bar to limit downward movement of said supporting member, said supporting member being adapted to fold up under said main bar and said link being adapted to lie along the vertical flange of said supporting member in the folded position of said bracket. 35
